UNITED STATES PATENT OFFICE.

GALY M. EDVENSON, OF WILLIAMS, IOWA.

HAY-RACK.

1,209,690.

Specification of Letters Patent. Patented Dec. 26, 1916.

Application filed June 1, 1916. Serial No. 101,078.

To all whom it may concern:

Be it known that I, GALY M. EDVENSON, a citizen of the United States, residing at Williams, in the county of Hamilton, State 5 of Iowa, have invented certain new and useful Improvements in Hay-Racks; and I do hereby declare the following to be a full, clear, and exact description of the invention, such as will enable others skilled in the art 10 to which it appertains to make and use the same.

This invention relates to the class of hay racks, and has particular reference to a bracket or fitting which greatly simplifies 15 the construction of baskets for hay racks.

The invention has for its object to provide a constructional element for use in building hay racks, consisting, more particularly, in providing a bracket for mounting 20 the superstructure or basket upon the body or floor frame. Owing to the lightness of the superstructure and the unevenness of the ground over which hay racks must usually be driven, it frequently becomes necessary to 25 use braces across the sides of the superstructure, or between the superstructure and the body of the rack in order to prevent the superstructure or basket from becoming disorganized, or so loosened as to swing back 30 and forth with the motion of the wagon. By means of the structure which is herein-after described, I am enabled to build a rack body and the accompanying superstructure or basket without the use of braces which 35 make the task of loading and unloading the rack very difficult. Furthermore by the use of my improved structural unit, I am enabled to remove the basket as a whole, in comparatively short time, the basket being 40 at the same time capable of rigid and secure attachment to the rack body.

With the above and other objects in view, as will hereinafter appear, my invention will now be fully set forth and described, reference being had to the accompanying drawings.

In said drawings, Figure 1 is a section transversely through a portion of a hay rack, constructed by the use of my invention, Fig. 2 is a section on line 2—2 of Fig. 1, Fig. 3 is a side elevation of a portion of a hay rack taken at one of the vertical posts, and Fig. 4 is a plan view of one of the elements of the bracket.

Referring more particularly to said drawings, 1 denotes a transverse stringer and 2

a longitudinal corner stringer of the body of a hay rack, said transverse stringers carrying the usual floor boards 3. Mounted upon the longitudinal stringers 2 are the vertical 60 posts or standards 4 which are joined by the spaced side-boards 5. As usual, the longitudinal stringers rise above the top-surfaces of the floor boards 3, so that a shoulder 6 is formed longitudinally of the body at each 65 side thereof.

Mounted upon the longitudinal stringers 2, and extending transversely thereacross are the base plates 7, said base plates 7 being provided upon their inner ends with the 70 feet 8 which bear upon the floor boards 3. The outer ends of the base plates 7 extend beyond the outer edges of the stringers 2, and provide bearings 9 for the vertical standards 10. The base plates 7 are secured 75 to the rack base or body preferably over the transverse stringers 1. A bolt hole through the foot 8 and another through the body of the plate provides means for holding each base plate 7 to the rack body, one of the 80 bolts being passed through the stringer 2 and the stringer 1 and the other bolt being passed through the foot 8, the floor 3 and the stringer 1.

Each of the supports 10 above mentioned 85 consists of a plate which extends vertically upward along the outer face of the post or standard 4, and usually underlies the first side-board 5, each support 10 being provided with a suitable number of bolt holes through 90 which the bolts 11 are passed to secure the support to the post 4. The lower ends of the supports 10 are provided with the threaded extensions 12, which pass through corresponding openings or bores in the bearings 9, and below the latter receive the nuts 13, which bearing against the lower face of the bearings 9 fix the standards 4 to the stringers 2, the feet of the posts or standards 4 resting upon the base plates 7.

The inner faces of the standards or posts 4 support the bracket plates 14, which are, or may be, of greater length than the supports 10, and terminate at their lower ends in out-turned feet 15 whose lower faces 105 correspond in conformation to the shape of the feet 8. The bolt which secures the foot 8 to the stringer 1 also passes through the foot 15 and securely clamps the latter to the foot 8. Also, the same bolts which pass 110 through the supports 10 and the posts 4 secure the plates 14 to the latter.

From the foregoing description it will be evident that I have provided a bracket by means of which the basket or superstructure of a hay rack may be readily attached 5 to the body of the rack, and as readily removed. When the rack basket is removed, the only portion of the bracket which remains is the base plate 7, which serves as a strengthening member to the body of the 10 rack, as well as a securing device for receiving the basket. When the basket is attached, the base plate becomes a support for the members 10 and 14, which are directly bolted to the base plate, the member 14 being bolted 15 as well to the transverse stringers 1. The member or plate 14 being a right angled structure, provides a rigid brace and support for the superstructure, so that all chance of the posts becoming loosened and rocking 20 with the swinging of the vehicle is practically eliminated. It may be, and probably will be desirable in the practical use of my improved device to use the plate 14 only upon some of the brackets, two or three of 25 the plates 14 on each side being sufficient to rigidly brace the superstructure against lateral movement, and the supports 10 upon each of the posts serve to securely fasten the superstructure to the body.

30 What I claim as my invention is:—

1. A structural element for hay racks comprising in combination with the body and the vertical posts of a hay rack, base

plates secured to the body along its longitudinal edges and overhanging the latter, 35 supporting plates upon the outer faces of said posts and projecting through the overhanging ends of said base plates, and bracket plates secured to the inner faces of said posts and having feet overlying the inner ends 40 of said bracket plates, and means securing said feet to said bracket plates.

2. A structural element for hay racks comprising in combination with the rack body including longitudinal stringers and 45 floor boards of a hay rack body, base plates carried by said longitudinal stringers and having their outer ends overhanging the free edges of said stringers, foot plates formed upon the inner ends of said base plates, vertical posts resting upon said base plates, supporting plates upon the outer faces of said posts having their lower ends extending through said overhanging ends 50 of the base plates, bracket plates upon the inner faces of said posts, and out-turned feet upon said bracket plates overlying the feet upon said base plates, and means securing 55 said bracket plates to said base plates and the rack body.

In testimony whereof, I affix my signature, in the presence of two witnesses.

60 GALY M. EDVENSON.
